UNITED STATES PATENT OFFICE.

WILLIAM GRAY, OF AMESBURY, MASSACHUSETTS.

DESIGN FOR A LAMP-BODY.

SPECIFICATION forming part of Design No. 36,116, dated October 21, 1902.

Application filed September 3, 1902. Serial No. 122,014. Term of patent 7 years.

To all whom it may concern:

Be it known that I, WILLIAM GRAY, a citizen of the United States, residing at Amesbury, in the county of Essex and State of Massachusetts, have invented a new, original, and ornamental Design for a Lamp-Body, of which the following is a specification.

Referring to the drawings which illustrate my new and original ornamental design for a lamp-body, Figure 1 is a front view in elevation. Fig. 2 is a side view in elevation. Fig. 3 is a top plan view.

The letter A designates the central or main body portion, which is elliptical in shape; B, a frusto-conical reflector extending inwardly from the front or face of the body; C, an ornamental beading encircling the front; D, the convex rear surface, with a projection at the center thereof; E, a lens set in the front of the body; F, the ornamental beveled edge of the lens; G, the curved surfaces of the sides of the body; H, a curved surface extending from the beading C to the curved surface G, as shown; I, a beading encircling the body at the junction of surface H with surfaces G of the side; J, the top of the lamp-body.

K designates a substantially rectangular disk located above the portion J, which latter 30 tapers upwardly and has four concave surfaces L, those opposite each other being of approximately the same area; M, an ornamental beading at the edge of the said rectangular disk; N, a concavo-convex cap circular in outline supported by uprights O some

distance above the rectangular disk; P, an ornamental circular beading below the uprights; Q, a curved handle; R R R, ornamental rivets arranged in series, as shown; S, a cylindrical portion projecting downwardly 40 from the main body portion; T, the concave surface of the portion S, which has an ornamental band U, circular in shape; V, an ornamental circular beading, and W is a convex surface joining the beading U and the 45 bottom.

To the eye the lamp-body as a whole presents the appearance of a structure having a main body portion elliptical in shape, from the upper part of which springs a top with 50 tapering concave sides surmounted by a rectangular disk, above which is located in a parallel plane a convex disk and from the lower part of which main body portion depends a cylindrically-shaped portion with a concave 55 circular surface, the said main body portion, top, and depending portions being provided with ornamental rivets and beadings disposed as set forth and shown.

Having described my invention, what I 60 claim, and desire to secure by Letters Patent, is—

The ornamental design for a lamp-body, as shown and described.

In testimony whereof I affix my signature 65 in presence of two witnesses.

WILLIAM GRAY.
